TO COOPER HEWITT ELECTRIC COMPANY, OF HOBOKEN, NEW JERSEY, A CORPORA-
TION OF NEW JERSEY.

ALTERNATING-CURRENT VAPOR-LAMP.

1,161,425.

Specification of Letters Patent Patented Nov. 23, 1915.

Original application filed May 11, 1905, Serial No. 253,953. Divisional of this application filed October 5, 1911. Serial No. 352,890.

To all whom it may concern:

Be it known that I, Percy H. Thomas, a citizen of the United States, and resident of Montclair, county of Essex, State of New Jersey, have invented certain new and useful Improvements in Alternating-Current Vapor-Lamps, of which the following is a specification.

My invention relates to improvements in vapor electric lamps and particularly to lamps of that character which are designed to be used on alternating current circuits.

I have illustrated in the present application various embodiments of the invention as will appear in the present specification.

One object of my invention relates to providing alternating current lamps of the tilting type and also providing means for starting the same into operation.

The various embodiments of my invention will be understood by reference to the accompanying drawing, in which I show an alternating lamp provided with a triple starting device including tilting parts, starting parts, and transfer parts.

In the drawing I show a form of circuits to be used in connection with an alternating current lamp. In the first instance the mercury puddles, shown at 32 and 33, are out of contact and when the circuit of the mains 34 and 35 is closed, current passes through the lifting magnet, 36, and by way of the wire or conductor, 37, to a cut-out, 38, and back to the line. Between the mains 34 and 35 are connected two choke coils, 39 and 40, and a point intermediate between the choke coils is connected through two magnets, 41 and 70, to the negative electrode, 43, of the lamp. The magnet 41 is in operative relation to the cut-out 38 while the magnet 70 is in operative relation to a cut-out, 44, in a circuit leading to the puddle 32 through a resistance, 45. The electrode 46 is connected by a wire, 49, to one of the mains 35 through a coil, 50, while the electrode 47 which electrode is surrounded by a shield 48 is connected by a wire, 60, through a coil, 51, in inductive relation to the coil 50, to the other main 34.

The magnet 36 being energized tilts the lamp from the operating dotted position to the full line or non-operating position where there exists a connection between the posi-

tive electrode 46 and the mercury in the pocket 32. Current then flows from the main 35 through the coil 50, the electrode 46, the mercury in the pocket 32, the resistance 45, the cut-out 44, the magnet 41, through the coils 39 and 40 to the source. This current in passing through the magnet 41 operates the cut-out 38 and deenergizes the coil 36 allowing the container to begin to drop and causing a separation between the pocket 32 and the electrode 46. This separation, may or may not initiate a permanent discharge between the positive electrodes 46 and 47 and the mercury in the pocket 32 as already described. In case it does not, the magnet 70 will again become energized and repeat its action until such permanent discharge be established. This discharge will act permanently through the coil 41 upon the cut-out 38 deenergizing the magnet 36 and allowing the container to drop by gravity to its operating position 75 transferring in this operation the negative electrode from the mercury of the pocket 32 to the negative electrode 43 through the agency of the coil 70 acting on the cut out 44, and the stream of mercury momentarily connecting the electrodes 32 and 43.

The magnets 70 and 41 remain in the circuit as inductive resistances.

This application is a division of my application Serial Number 253,953, filed May 11, 1905.

I claim as my invention:

1. The combination with a rectifier having a plurality of anodes, of a source of current therefor, reactive means between said source and said anodes wound to magnetize in the same direction for current to either anode and means for establishing initial current flow in one of said reactive means, the said means consisting of a starting cathode in contacting relation with the appropriate anode.

2. The combination with a rectifier having a plurality of anodes, of a source of current therefor, reactive means between said source and said anodes wound to magnetize in the same direction for current to either anode and means for establishing initial current flow in one of said reactive means, the said means consisting of a starting cathode in contacting relation with the appro-

priate anode and means for transferring the cathode spot on said starting cathode to the working cathode upon initiation of operation on the starting cathode.

3. The combination of an alternating source, a vapor rectifier connected therewith, a current smoothing reactance for the load circuit connected to the anode side of the rectifier and having separate coils for each anode circuit, said coils being wound to magnetize in the same direction and an inductance coil in the lead of the cathode connected to an intermediate point of said source.
6. 3. The combination of an alternating source, a vapor rectifier connected therewith, a current smoothing reactance for the load circuit connected to the anode side of the rectifier and having separate coils for each anode circuit, said coils being wound to magnetize in the same direction and an inductance coil in the lead of the cathode connected to an intermediate point of said source.

Signed at New York, in the county of New York and State of New York, this 4th day of October, A. D. 1911.

PERCY H. THOMAS.
